FLASHLIGHT HAVING MULTIPLE LAMPS
FOR VARIOUS ILLUMINATING EFFECTS

Vance L. Allen, Wichita Falls, Tex.

Application October 22, 1946, Serial No. 704,830

3 Claims. (Cl. 240—10.6)

1

This invention relates to improvements in flashlights, and more particularly to the type of flashlights having multiple lamps for various illuminating effects.

Heretofore, most flashlights have used a single lamp with a set of one or more batteries for supplying electric current thereto. The batteries soon lose their energizing effect and when that results, it is necessary to replace the batteries with a new set, it being impossible to obtain illumination in the meantime. Some suggestions have been made heretofore for combining a plurality of lamps in a single casing, but this has involved a mere duplication without obtaining any cooperating benefit therefrom nor the possibility of variation of light as a result of thus combining the lamps.

One object of this invention is to provide a flashlight with at least two sets of batteries which may be used independently for respective illuminations or may be connected together to provide increased illumination by supplying higher voltage to a single lamp, which will result also in longer burning capacity.

Another object of the invention is to provide in a flashlight for so controlling the supply of electric current to respective lamps, that these may be used independently as desired or the sources of current be connected to one lamp for obtaining greater energizing effect thereof and better illumination.

Another object of this invention is to provide a combination of switches for a flashlight whereby two sets of batteries may be used independently for lighting independent lighting elements, or two sets of batteries may be combined to provide higher voltage for lighting a third lighting element having a different electrical resistance value, and having the switches so arranged as to prevent backflow of current through the other circuits when any particular circuit is used.

The invention may be embodied in a flashlight in which multiple sets of batteries may be mounted in a casing and arranged for the independent supply of electric current to respective lamps, whereby to obtain illumination from either of these as desired. The construction preferably is such that both sets of batteries may be connected with one lamp to produce the illuminating effect created thereby.

This embodiment of the invention is illustrated in the accompanying drawings, in which:

Fig. 1 is a top plan view of the complete flashlight;

Fig. 2 is a sectional view through one end portion thereof, taken on the line 2—2 of Fig. 1, with parts broken away;

2

Fig. 3 is a sectional view through the opposite end portion thereof, taken on the line 3—3 of Fig. 1, and with parts broken away;

Fig. 4 is a cross section through one of the switches, on the line 4—4 of Fig. 2;

Fig. 5 is a perspective view of the switches and electrical connections detached;

Fig. 6 is a diagrammatic view of the electrical circuits of the flashlight; and

Fig. 7 is a fragmentary sectional view taken on the line 7—7 of Fig. 1.

In the form of flashlight illustrated in the drawings, a casing generally indicated at 1, is formed as an elongated tubular shell, which may be formed of fiber as shown or sheet-metal drawn to the desired size and shape and properly insulated. The casing 1 is open initially at both opposite ends.

The casing 1 is divided transversely intermediate its ends by an insulating disc 2 which separates the casing 1 into respective compartments 3 and 4. The disc 2 is retained in place preferably by circumferential indentations 5, rolled into the tubular shell 1, on opposite sides of the disc 2, forming ribs on the inner wall of the shell confining the disc therebetween.

The compartments 3 and 4 are adapted to receive batteries 6 and 7, respectively, which are shown in sets of two cells in each of the chambers, although one or more cells may be used in each chamber, if desired. Each of these battery cells is of the usual character ordinarily provided in flashlights and having a carbon electrode enclosed within the usual zinc container which in turn is insulated from the casing by a surrounding cardboard thereon. The plurality of cells shown are arranged in series relation with the carbon electrode of one cell electrically connected with the zinc container of the adjacent cell by direct bearing relation therebetween.

As shown in Fig. 3, the outer end of the chamber 3 is provided with a reflector head 8, having a screw-threaded connection 9 with the end of the casing 1. The head 8 carries the usual flashlight reflector 10 therein within which is screw-threaded an incandescent bulb 11, that is screw-threaded into a ferrule 12, attached to the reflector 10.

Surrounding the ferrule 12 and mounted thereon, is an insulating disc 13 which carries a U-shaped contact member 14, extending across and in bridging relation with the carbon electrode at the end battery cell 6, between said carbon electrode and the end contact of the lamp 11, to form an electrical connection therebetween. The contact member 14 is connected with a surround-

ing ring 15, the edge 16 of which is flared inwardly for a purpose hereinafter described.

At its opposite end, the casing 1 supports a reflector head 17, as shown in Fig. 2, within which head is mounted a reflector 18. The head 17 has a central ferrule 19, internally screw-threaded, and within which a lamp 20 is detachably mounted in the usual way.

The lamp 20 preferably is constructed with multiple filaments, two of which are shown and designated respectively at 21 and 22. These preferably are of different resistance properties and are adapted to be energized by different currents, such as high and low voltages, as three volts and six volts, respectively. One side of each filament is connected with the end contact 23 which is in bearing relation and electrically engaging a carbon electrode of the end battery cell 7. The opposite side of the filament 21 is connected with a surrounding conductor ring 24, formed on the lamp 20, while the opposite side of the filament 22 is connected with the threaded base 25 of the lamp, which base is screwed into the threaded ferrule 19 in conducting relation therewith.

The reflector head 17 carries an insulating disc 26 which also extends around the ferrule 19 and upon which disc 26 is mounted a conducting ring 27, having an inwardly flared edge 28. The conductor ring 27 carries spring contacts 29 thereon, in position to bear against the contact portion 24 of the lamp 20 to provide an electrical connection thereof with the lamp and with one side of the filament 21.

The series or sets of batteries 6 and 7 are pressed outwardly, respectively, by coiled springs 30 and 31, which are interposed between the inner ends of the sets of batteries and the insulating disc 2, and tending to urge the outer carbon electrode of each battery into electrical engagement with the corresponding lamp 11 or 20. The inner ends of the coiled springs 30 and 31 may be secured in place by clips 32 and 33, respectively, extending over the upper edge of the insulating disc 2 and crimped or clamped thereon, as will be evident from Fig. 5.

Extending lengthwise of the casing 1, in side-by-side relation, are strip conductors 34 and 35, which are separated from the casing 1 by an internosed sheet of insulating material 36. The conductors 34 and 35 extend over the clips 32 and 33, respectively, and in contact relation therewith for electrical connection between said conductors and the clips.

Arranged in longitudinal alignment with the conductors 34 and 35, at one end of the flashlight, are conductor strips 37 and 38, respectively. In like manner, conductor strips 39 and 40 are arranged in longitudinal alignment with the conductors 34 and 35, respectively, at the opposite end of the flashlight. The conductor strips 37 and 38 are provided with contacts 41 and 41', respectively, on each of the outer ends thereof, in position to engage in contact relation with the reflector head 8 and the contact ring 15, respectively, when the reflector head 8 is inserted and secured in place in the end of the casing 1. In a similar manner, the conductor strips 39 and 40 have contacts 42 and 42', thereon in position for contact relation with reflector head 17 and the contact ring 27, respectively, when the reflector head 17 is adjusted into proper position on the casing 1.

The conductors 34 and 35 are adapted to be connected with the conductor strips 37-40 at

the respective opposite ends thereof through switches generally indicated at 43 and 44. Each of the switches 43 and 44 is constructed with a slide 45 slidably mounted within a guide 46 which retains the slide in place and limits and guides the sliding movement thereof. Each of the contact arms has indentures on the outer ends thereof to register with the respective aligned contacts to maintain the switches in adjusted positions.

The slide 45 for the switch 43, a two-position switch, carries a pair of bridging contact arms 47 and 48, each of which is insulated from the slide and secured thereto by a rivet or screw 43'. The contact arm 47 is adapted to engage contacts 49 and 50, when the slide 45 is in one extreme position, while the contact arm 48 is adapted to engage contacts 51 and 52 when the slide 45 is in the opposite extreme position. The contacts 49-52 are carried respectively by the conductors 34, 37, 35 and 38. The contact arms will establish an electrical connection between either pair of the adjacent, aligned conductors when engaging the contacts thereof at opposite ends; however, the contacts are so positioned that only one pair of contacts of aligned conductors are in contact with contact arms 47 or 48 at one time.

The switch 44, a three-position switch, in like manner, has contact arms 53 and 54 carried by the slide 45 of the switch 44, and which arms are secured thereto by rivets or screws 55, while separated by an insulating washer from contact relation with the slide.

The contact arm 53 is in position to engage contacts 56 and 57 in one extreme position of the slide 45 of the switch 44, which contacts 56 and 57 are carried respectively by the conductors 34 and 39. The contact arm 54 is in position to engage contacts 58 and 59 when the slide 45 of the switch 44 is in the opposite extreme position. The contacts 58 and 59 are carried by conductors 35 and 40 respectively. In this manner, the contact arms bridge the respective conductors and establish electrical connections therebetween, either pair of aligned conductors 34-39 or 35-40 can be closed by moving switch 44 to the extreme inward or outward position to complete a circuit; however, both circuits cannot be closed at the same time. A third position intermediate the end positions is an "off" position, and a dummy contact 57' is provided to register with an indenture in contact arm 53, so switch 44' will be held in an adjusted position.

It is possible, according to this invention, to energize either the lamp 11 by the battery 6 or the low voltage filament 21 of the lamp 20 by the battery 7, or to combine the energy of both batteries 6 and 7 for energizing the high voltage filament 22 of the lamp 20. The filament of the lamp 11 is also low voltage, approximately three volts, the same as the filament 21 of the lamp 20, whereas the filament 22 is of high voltage, approximately six volts.

When the switch 43 is moved to an outward position to engage the slide 47 with the contacts 49 and 50, the circuit is closed through battery 6, filament of lamp 11, through ferrule 12 and reflector 10, through contact 41 which is adapted to engage reflector 10, and which contact 41 leads through conductor 37 to contact points 49 and 50 and thence through switch element 47, conductor 34 and clip 32, to spring contact member 33 to complete the circuit through the battery 6. This will energize lamp 11 to produce illumination. At this time the slide 48 is out of bridging relation with contacts 51 and 52.

When it is desired to energize the low voltage filament 21 of the lamp 20, the slide 45 of the switch 44 is moved in an outward direction to cause a bridging relation between the contacts 58 and 59. This will close the circuit from the battery 7 through the end terminal 23 of the lamp 20, thence through the filament 21, the conductor ring 24, spring contact 29, contact ring 27-28, contact point 42', conductor 49, contacts 59 and 58 through slide 54, conductor 35, clip 33 and spring 31 to the battery 7. At this time, the slide 53 is out of bridging relation with the contacts 56 and 57.

Normally the flashlight will have the switches in such position that none of the filaments will be energized. When the switch 43 is in this position the contact arm 48 will bridge contact points 51-52; therefore, when it is desired to close the circuit through the high voltage filament 22 of lamp 20, switch 44 is moved inward so that contact arms 53 will bridge contact points 56-57 so that the electrical energy flowing through batteries 6 through contact member 14, contact ring 15-16, through contact member 41' and through conductor 38, through the contact points 51-52 and contact arm 48, through conductor 35 to point of contact with clip 33, thence through clip 33, through contact spring 31, through battery 7 to contact 23, thence through filament 22 to threaded base 25, through threaded ferrule 19 to reflector head 17, and through contact 42, as shown in Fig. 7, to conductor 39, thence through contact points 56-57 and contact arms 53, through conductor 34 to where contact 34 engages spring clip 32, thence through spring clip 32 and contact spring 30 to the negative side of the battery, so as to complete the circuit through both batteries 6 and 7. This will energize filament 22 with the full current of both batteries 6 and 7, operating the lamp at the high voltage produced thereby.

By having the batteries arranged and connected in the manner described, the flashlight has the advantage of a four-cell lamp or six volts, or may be operated as two two-cell or three-volt lamps. Either or both of the three-volt lamps may be used simultaneously or independently as desired, which is especially advantageous if either of the sets of batteries or lamps should become burned out. When the combination of both sets of batteries 6 and 7 are connected together by switches 43 and 44, the contact arms 47 and 54 are out of bridging relation with their respective contacts, thereby preventing a short circuit through either of the low voltage filaments, while the high-voltage circuit is in use, without endangering either of the low-voltage filaments.

While the invention has been illustrated and described in one embodiment, it is recognized that variations and changes may be made therein without departing from the invention, except as specified in the claims.

I claim:

1. In a flashlight, a casing adapted to have a battery mounted therein, a reflector assembly mounted on each end of the casing, a lamp socket in each reflector assembly, a lamp mounted in each of said sockets in position for electrical connection with the battery, a pair of longitudinal electrical conductors positioned within said casing and extending substantially from end to end thereof, said conductors being separated intermediate their ends, insulating means to insulate said conductors from each other, a conductor ring on each end of said casing in contact with one of said

conductors, one of said longitudinal conductors being in position to contact both of said reflectors, a pair of switches intermediate the length of said longitudinal electrical conductors, said switches including a pair of contact arms, said contact arms being adapted to form a bridging connection within the length of said longitudinal electrical conductors so as to connect electrically said longitudinal electrical conductors to provide an electric circuit therethrough, an insulation member intermediate the length of said casing, a pair of contact elements spaced apart and mounted on said insulating member and in contact with said longitudinal conductors, said flashlight casing having circumferential grooves formed on either side and in contact relation with said insulating member so as to bind said insulating member in contact relation with said conductors, a pair of spring contact elements mounted on either side of said insulating member and connected to said contact elements and adapted to contact one end of a battery to keep the opposite end of said battery in contact with said lamp.

2. A flashlight comprising a plurality of electric lamps, each of said lamps having a main filament, one of said lamps having an auxiliary filament requiring approximately double the voltage of said main filament, separate batteries each of sufficient voltage to operate one of said main filaments, main electrical circuits connecting each of said main filaments with one of said batteries, an auxiliary electrical circuit connecting said batteries in series with said auxiliary filament, switches in said main circuits for opening and closing the same, and switch means in said auxiliary circuit effective only upon opening movement of said switches for closing said auxiliary circuit and upon closing movement of one of said switches to open said auxiliary circuit.

3. A flashlight comprising an elongated tubular casing, electric lamps mounted at opposite ends of said casing, each of said lamps having a main filament, one of said lamps having an auxiliary filament requiring approximately double the voltage of said main filament, separate batteries each of sufficient voltage to operate one of said main filaments, main electrical circuits connecting each of said main filaments with one of said batteries, an auxiliary electrical circuit connecting said batteries in series with said auxiliary filament, switches in said main circuit for opening and closing the same, each of said switches including means operable by movement in one direction to close a main circuit and in the opposite direction to open a main circuit, and switch means effective upon movement of one of said switches in one direction for opening said auxiliary circuit and upon movement of said switches in their opposite direction for closing said auxiliary circuit.

VANCE L. ALLEN.
